DESIGN.

W. J. NOBLE,
A BURIAL CASKET.

No. 19,567.

Patented Jan. 7, 1890

A

UNITED STATES PATENT OFFICE.

WILLIAM J. NOBLE, OF NEW YORK, N. Y.

DESIGN FOR A BURIAL-CASKET.

SPECIFICATION forming part of Design No. 19,567, dated January 7, 1890.

Application filed November 11, 1889. Serial No. 329,939. Term of patent 7 years.

To all whom it may concern:

Be it known that I, WILLIAM J. NOBLE, a citizen of the United States, residing at the city, county, and State of New York, have 5 invented and produced a new and original Design for Burial-Caskets, of which the following is a specification.

The leading feature of my design consists of a series of lines or figures representing 10 interlaced draperies.

The figure represented in the accompanying photograph illustrates a side elevation of a casket decorated in accordance with my design.

15 Upon the body A of the casket a series of curved lines a are drawn, which lines are so grouped as to form a series of crescent-like figures B, said figures having the appearance of being interlaced and attached to the casket.

20 In arranging the figures B the lines a are so drawn that the lines of two figures seem to

intersect or meet over the center of a third figure, and the said lines a are further so shaded as to cause each figure B to have the appearance of consisting of a series of concentric folds. 25

This design is usually embellished by intersecting lines and figures seemingly pendant from the convex of the base-line of each figure B, drawn in imitation of fringe. 30

In producing the design upon the casket the several lines are so drawn and the figures are so arranged and shaded as to impart to the completed design a highly ornamental yet pleasing somber appearance. 35

I claim—

The design for burial-caskets herein shown and described.

WILLIAM J. NOBLE.
